CONTROL FOR FREE PISTON ENGINES

Willard A. Morain, Hamilton, Ohio, assignor, by
mesne assignments, to Baldwin-Lima-Hamilton
Corporation, a corporation of Pennsylvania

Application May 24, 1950, Serial No. 163,974

4 Claims. (Cl. 123—46)

1

This invention relates to free piston internal combustion engines and is particularly directed to a simplified mechanism for controlling the return stroke of the pistons in such an engine.

In the operation of free piston engines, some means must be provided to return the pistons to the proper position within the engine cylinder for compression of the charge of air therein. Where the engine is used on a part of an air compressor operating at constant load, the re-expansion energy of the air in the compressor may be utilized to return the pistons. However, in the case of the engine being used as a power gas generator and operating at variable load, it is necessary to resort to the use of an additional cylinder or chamber wherein the proper piston restoring energy can be developed. Such a chamber is known as a "bounce" chamber, and by adding air to or venting this chamber it is possible to govern the inward piston stroke within relatively close limits.

It is known in the art to accomplish control of the bounce chamber energy in various ways. See, for example, the patent to Lewis, 2,435,970. The present invention is primarily directed to a simplified control structure in which the bounce chamber energy is related to the load on the engine, the latter being reflected in a change in exhaust pressure.

The primary object of the invention is to provide a control device of the above character which is simple and efficient in operation and which is not likely to get out of adjustment after long continued use.

Another object of the invention is to provide a control for a power gas generator that is operated in conjunction with a turbine of fixed nozzle area, the control being arranged to correlate gas generator bounce pressure and exhaust to maintain proper stroke length in the gas generator.

Other objects and advantages of the invention will become apparent from the following specification, reference being had to the accompanying drawings in which:

Fig. 1 is a diagrammatic view, partly in section, of a free piston engine embodying the present control device;

Fig. 2 is a central vertical sectional view somewhat diagrammatic, of a suitable control device embodying the invention; and

Fig. 3 is a fragmentary sectional view of a modification introducing additional control pressure.

Referring to the drawings, the present invention is shown in connection with a free piston

2

power gas generator designated generally 10, having at each end a bounce chamber 11 connected by an equalizing line 12. The gas generator includes the usual integral multiple pistons fitting in power cylinders 14, compressor cylinders 16 and the bounce cylinders or chambers 11. The compressor cylinder 16 is also utilized as a reverse bounce chamber 17 in a manner set forth in the above identified Lewis patent. It will be appreciated that, if the engine is to operate by compression ignition the power pistons must reach an inward point such that the air between them is at the proper temperature and pressure to ignite an injected fuel charge, but must not approach each other too closely, thereby restricting the volume into which the fuel may be injected or raising the temperature and pressure of the air charge beyond practical limits. Excessive pressure in the bounce chambers will also tend to stall the engine by restricting the length of the outward strokes of the pistons and preventing proper scavenging of the power cylinder. It is therefore, important that the energy available in the bounce chambers for returning the pistons be maintained at the proper level required for a given load condition. Further, it is not desirable that the devices intended to control the piston restoring energy be responsive to each minute change in stroke length, since such devices will exhibit a tendency to "hunt" above and below the proper energy level. It is sufficient that pronounced trends toward changes in stroke length be followed, so that the present invention introduces oscillation damping means in the control circuit.

The present invention comprises regulating valve means constructed and arranged to vent or add air to the bounce chambers as the engine exhaust pressure decreases or increases. Broadly, control of the stroke length of a free piston engine by regulating the quantity of air in a bounce chamber is known in the art, but prior devices have relied on complicated equipment to balance pressures in various engine chambers, and have proved difficult to adjust and maintain.

The valve means of the present invention is indicated somewhat diagrammatically in Fig. 2 and comprises a body 20 having an upper connection 22 to the engine exhaust line, a connection 24 to a source of high pressure air such as a storage bottle 26, and two connections, 28 and 30, to the bounce cylinder equalizing line 12. Connection 28 is deliberately restricted so that small fluctuations do not affect the control elements. The "damped" connection thus provided

3

permits the control to respond to variations in the mean pressure in the bounce chamber equalizing line and not to the maximum and minimum pressures therein. No attempt has been made to indicate the manner in which the valve body 20 is assembled.

A cylinder 32 at the top of the valve body 20 communicates directly with connection 22, and a piston 34, working in this cylinder is thus subjected to the control pressure which may be either exhaust pressure, or the sum of exhaust and reverse bounce pressures, at all times. Piston 34 is biased inwardly of its cylinder by a regulating spring 36 interposed between an extension 31 of the piston and a head 38 of a movable valve seat 40. Head 38 is attached at the center of a diaphragm 42, the outer edge of which is sealed in the body 20.

The movable valve seat 40, of which head 38 forms the upper end, is guided for linear movement in a bore 44 of the body 20, by a packed piston-like flange 46 and is provided with a central passage 48 which opens into a vented chamber 50 above the diaphragm. A valve 52 normally closes passage 48 by sealing engagement with the lower end of the movable valve seat 40.

Valve 52 is preferably provided with a guiding stem 54 which cooperates with a suitably formed part of the body 20 to assure linear movement to the valve. The valve is biased upwardly by a spring 56 interposed between a plate valve 58 and a stationary body part 60, the plate valve engaging a stem extension 62 of the valve 52. Valve 52 is limited in its upward movement by a series of projections 64 extending into the bore 44 in the path of movement of the valve.

A chamber 66 around valve 52 communicates with damped connection 28 to the direct bounce cylinder equalizing line 12 by means of passages 68 and 72. Thus, when the valve is opened by a separating movement of seat 40 and the head of the valve, chamber 66 and hence the bounce cylinders will be vented through passage 48 and chamber 50.

Passage 72 in the body 20 opens into a chamber 74 below the diaphragm 42 so that the underside of the diaphragm is subjected to the existing mean pressure in the bounce cylinder equalizing line and is urged upwardly thereby. This force is opposed by the force exerted by the control pressure acting on piston 34 and transmitted through spring 36 and head 38. Proper selection of the relative areas of piston 34 and diaphragm 42 makes it possible to provide a control suitable for a wide range of systems, primary dependence being on the operating characteristics of the associated turbine or other gas consumer.

Suitable means are also provided to add air to the bounce chambers by opening communication between high pressure air connection 24 and bounce cylinder charging line 30. This connection is controlled directly by a lower valve 80 disposed in a chamber 82 in the body 20, the chamber 82 being constantly connected to the source of high pressure air.

Lower valve 80 is carried by a stem 84 formed on the lower side of a piston 86 working in a cylinder 88 in the valve body. The stem 84 has a central passage 90 extending through it which communicates with the cylinder 88 above the piston 86, but the passage is restricted at its upper end, as by an orifice 92. The lower face of piston 86 is subject to the pressure of chamber 82 and the charging air by reason of a direct-

4

ly connecting passage 94. Thus, the upper and lower faces of the piston are under the same pressure when conditions are stable, but if cylinder 88 were suddenly vented and pressure in the upper piston face relieved, it will be seen that the pressure on the lower piston face would predominate until air passing through the restricted end of passage 90 could again fill the cylinder to the initial pressure. Under certain conditions of unbalanced pressure, then, piston 84 moves upwardly in its cylinder and charging valve 80 is opened. A spring 96 biases the piston downwardly to close valve 80 when the pressures again balance on the upper and lower faces of piston 86.

Cylinder 88 is controlled at its upper end by plate valve 58, and is vented, when this valve is opened, through passage 70, into the bounce air control circuit. The cylinder could be vented to atmosphere, but it is preferred to conserve the available air.

In operation, assuming the power gas generator to be running at normal stroke and frequency properly to supply gas to an associated turbine T, the control device above described will come into operation only upon a deviation from the proper operating conditions. If the control pressure rises for any reason the pressure in top cylinder 32 rises and piston 34 moves outwardly against the tension of regulating spring 36. Diaphragm 42 is thus lowered and the movable valve seat 40 and its associated valve 52 are likewise lowered so that plate valve 58 is opened while valve 52 remains closed. This condition would also be realized if for any reason the bounce spaces became undercharged and limited the pressure under diaphragm 42.

When plate valve 58 leaves its seat, air in lower cylinder 88, being under full supply pressure, rushes into the control system through passages 70 and 72. The forces on the two faces of lower piston 86 are thus unbalanced, there being a greater pressure on the lower face than on the upper. The piston is thus moved upwardly in its cylinder and the lower valve 80 is moved off its seat against the action of spring 96. High pressure air from the storage bottle 26 thus enters the bounce chamber equalizing line and the bounce cylinders themselves. Thus more energy becomes available to force the engine pistons towards each other on the compression stroke, compensating for the increased exhaust pressure or scavenging air.

As the bounce pressure is raised to the point where the desired balance is again reached, the pressure on the under side of diaphragm 42 forces the diaphragm and its associated movable valve seat 40 upwardly allowing spring 56 to again seat plate valve 58 and prevent further escape of air from lower cylinder 88. As air from the high pressure source continues to pass through passage 90 and the restriction 92, the pressure above and below lower piston 86 soon becomes balanced and spring 96 can move the piston and valve 80 downwardly to seat the latter and close communication to charging line 30.

If for any reason the exhaust pressure is reduced from the normal operating condition, or if for any reason the bounce cylinders become overcharged, diaphragm 42 is moved upwardly to compress spring 36 due to the now excessive pressure on its under face. The movable valve seat 40 is thus moved away from valve 52 since the valve can follow the seat only to the limit deter-

mined by the projections 64 in the bore 44. Since passage 48 is now open, venting into chamber 50 and to atmosphere can take place from the bounce cylinder equalizing line through damped connection 28, passages 72, 70 and 68. As the pressures are again balanced, diaphragm 42 will return to its normal position and valve 52 will again close.

It will thus be seen that the bounce energy will be adjusted in accordance with changes in load as reflected in a variation of the exhaust pressure and, at any given load condition, will be corrected for under-charge or over-charge resulting from any other cause such as leakage past the pistons, etc.

In the modification shown in Fig. 3, additional control pressure is introduced by extending a line 100 from a reverse bounce equalizing line 102 connecting the two reverse bounce chambers 17. The line 100 is connected to the top cylinder 32 which is now broken down into two axially concentric cylinders 32, 32a. Cylinder 32 is connected to the exhaust line through conduit 22 while cylinder 32a is connected by line 100 to the reverse bounce equalizing line. Piston 34 is now shown as a stepped piston comprising a lower portion 34a operating in cylinder 32a and an upper portion 34 operating in cylinder 32. The composite piston is thus subjected to the sum of the reverse bounce pressure and the exhaust pressure and a significant variation in either will cause operation of the elements heretofore described to increase or decrease the bounce pressure of the engine. If the reverse bounce pressure is increased the frequency of operation of the engine is likewise increased in accordance with the disclosure of Lewis Patent 2,435,970. An increase in reverse bounce pressure causes an increase in the direct bounce pressure but operation of the present engine with the over-all effect that the engine runs at a higher frequency and greater load and supplies considerably more gas to the turbine or other consumer.

The addition of control by means of the reverse bounce pressure is also advantageous in the event that the system includes more than a single free piston power gas generator since control of the frequency of operation is more readily obtainable by variation in the reverse bounce pressure than by any other means so that more accurate synchronism can be maintained between a multiplicity of gas generators.

While the invention has been disclosed in connection with a particular form and disposition of the parts numerous modifications and changes may be made without departing from the scope of the appended claims.

What I claim is:

1. In an apparatus for controlling a free piston engine having a chamber in which air is compressed by a movement of the free pistons and subsequently utilized to return energy to the system by re-expansion, the improvement comprising an element subject on one side to the average pressure in said chamber and on the opposite side to a second pressure which reflects an operating characteristic of the free piston engine, a valve seat attached to and movable with said element, a valve normally closed on said valve seat and disposed to follow the movements thereof, means to limit the movement of said valve in one direction to effect a separation of said valve and seat upon continued movement of said seat in one direction, a second valve opened by movement of said first valve in the opposite direction, and means operated in response to an opening of said second valve to admit air to said chamber.

2. The improvement defined in claim 1 in which said last means includes a cylinder in communication with a source of high pressure air, and a piston controlled valve normally closing communication between said cylinder and said engine chamber, said piston controlled valve normally closing communication between said cylinder and said engine chamber, said piston controlled valve being opened when said second valve is opened.

3. The improvement defined in claim 1 in which said element comprises a diaphragm urged in one direction by pressure in said engine chamber and in the opposite direction by a pressure corresponding to engine exhaust pressure.

4. The improvement defined in claim 1 in which said element comprises a diaphragm urged in one direction by pressure in said engine chamber and in the opposite direction by a pressure corresponding to the sum of engine exhaust pressure and pressure in an engine reverse bounce cylinder.
